UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING COMPANY, A CORPORATION OF MASSACHUSETTS.

HIGH-TENSION ELECTRIC SWITCH.

Application filed April 23, 1921. Serial No. 463,773.

To all whom it may concern:

Be it known that I, GEORGE A. BURNHAM, a citizen of the United States, residing at Saugus, in the county of Essex and State of 5 Massachusetts, have invented an Improvement in High-Tension Electric Switches, of which the following is a specification.

This invention relates to electric switches particularly adapted to control circuits of 10 relatively high potential and has particular reference to a switch characterized by a cylindrical shell or casing adapted to contain oil and bearing a stationary contact member at the bottom thereof; and a rod comprising a movable switch member and movable through an aperture in the cover of said casing to engage and disengage the stationary contact member; and baffle plates in said casing adapted to assist in quenching the 20 arc drawn between said rod and contact member during operation of the switch to interrupt the circuit.

An object of this invention is to provide a switch of the type above set forth 25 with means to absorb energy developed within the switch due to circuit interruption and specifically, to protect the cover of the receptacle and the baffle plates therein from damage due to the sudden generation of 30 high and possibly localized, gaseous pressures within the switch.

A further object is generally to improve the construction and operation of an electric switch of the type above set forth.

35 Certain features of this invention are set forth in my Patent No. 1,413,156, issued April 18, 1922, and this invention has more particular reference to the adaptation of the principle disclosed in said patent to the type 40 of switch herein set forth. Other features of this invention are disclosed in a co-pending application of Joseph N. Mahoney, Serial No. 488,150, filed July 28, 1921, and as signed to Sears B. Condit.

45 Fig. 1 is a front view of a switch embodying the invention with one of the switch units in section.

Fig. 2 is a front view of one of the switch units illustrating a modified manner of 50 resiliently mounting the oil receptacle.

As here shown the switch embodying the invention, includes the cylindrical shell 10, usually of drawn steel and of substantial length as compared with its diameter and

adapted to contain oil in which the switch 55 members are immersed. Said shell or casing is formed with a reduced bottom portion or neck 11 adapted exteriorly to be received in a supporting structure hereinafter to be set forth, and adapted interiorly to receive 60 the stationary contact member 12 which is electrically connected with the casing. The casing is provided with a cover 13 and said cover is formed with an annular flange which is received within the casing and in 65 sliding contact and electrically connected with said casing.

Said cover is formed with an aperture therethrough and a plate 14 is bolted on the cover over the aperture and bears an insulating bushing 15; and said bushing has an aperture 16 therethrough through which the switch rod 17 is adapted to move to make and break contact with the stationary contact member 12. Said switch rod is secured 75 to the arm 18 of operating mechanism of more or less usual construction.

It is customary to mount two switch units side by side on a supporting structure 19 and connect the units in series; and it is 80 also common to provide a brush member secured to the arm 18 of the operating mechanism to make electrical contact with the covers of the two units whereby electrically to connect them and shunt the oil immersed 85 contacts. For this purpose it is desirable to establish electrical connection between the cover 13 and the casing 10; and the flexible conductor 20 secured under a bolt 13^a of the cover and a bolt 10^a secured in the side wall 90 of the casing accomplishes the result.

The switch units are herein shown as supported on the base 21; and said base is supported on an insulator 22 carried by the supporting structure 19 and secured thereto 95 by the stud 23 which forms one of the switch terminals.

Said base 21 is formed with supporting means for the casing 10 including the lugs 25 disposed to provide an enclosure for the 100 reduced portion 11 of said casing and support it against lateral movement; and the bottom of the casing is adapted to rest upon the base 21. Rods 27 are secured to the base 21 and extend upwardly along the casing 10 and are slidably received in apertures in the cover 13. Said rods are extended beyond the top of the cover and compression

springs 28 are received thereon and engage the cover and nuts 29 removably secured to said rods. This construction provides means whereby the cover may move upwardly with respect to the casing upon the occurrence of abnormal gaseous pressure conditions within the switch and thereby reduce strains upon the cover, securing means bushing and the like which heretofore have sometimes been so great as to cause the rupture of the parts enumerated.

In the modification illustrated in Fig. 2, said rods 27 are rigidly secured to the cover and the casing 10 is resiliently supported upon the compression spring 35 received between the lugs 25 of the base 21. In this construction the casing yields relatively to the cover to increase the gas expansion space above the oil in the casing and reduce gaseous pressure within the switch and strains upon the switch components resulting from such pressures.

The casing is provided with one or more baffle plates 40 which are disposed in vertically spaced relation within the casing; and are provided with apertures 41 therein through which the switch rod 17 is extended.

It has been customary, heretofore, to secure said baffles rigidly within the casing. I prefer to support said baffles yieldingly in place within the casing whereby they may yield relatively to each other and the casing to absorb shocks. A suitable structure for this purpose may include the vertically disposed rods 45 upon which said baffles are slidably received, and compression springs 46 may serve yieldingly to support said plates in position. Said upper baffle plate may be fixed to the upper ends of said rods, as by the pins 47 and springs 48 may extend between said rods and the cover to maintain said rods and plate yieldingly in place.

It will be observed that, with the construction above set forth, the switch components subject to gaseous pressures, or it may be, impact of the oil within the casing thrown upwardly by the rapid generation of gas at the arc are mounted to yield and thereby absorb shock and reduce the stresses in their connection with associated switch components.

While I have shown herein a construction wherein the cover is movable relative to the casing and also a construction wherein the cover is rigidly supported in fixed position and the oil receptacle is arranged for downward movement relative to the cover, I prefer the latter arrangement which is shown in Fig. 2, for the reason that the cover forms a contact member for the brush member, and it is desirable that said cover be maintained in a fixed position relative to said brush member as with the construction illustrated in Fig. 1, said cover may conceivably be moved upwardly by gaseous pres-

sure conditions within the casing to again contact with the brush member, with the result that the arc would then be drawn in air and not in oil as is the intent of the switch embodying this construction.

It is obvious that the construction may be otherwise modified without departing from the spirit of the invention.

I claim.

1. An electric switch having the combination of a cylindrical casing adapted to contain oil, a contact member mounted in the bottom of and electrically connected with said casing, means to support said casing vertically in position including a cover disposed on top of said casing, and yielding means arranged to provide for a relative movement between said cover and receptacle, and an independently-supported switch rod vertically movable through an aperture in said cover to engage the contact member contained in the casing.

2. An electric switch having the combination of a cylindrical casing adapted to contain oil, a contact member mounted in the bottom of said casing and connected electrically with said casing, means to support said casing vertically in position including a cover disposed on top of said casing and yielding means connecting said casing and supporting means arranged to provide for a downward movement of said casing due to circuit interruption, and an independently supported switch rod vertically movable through an aperture in said cover to engage the contact member contained in the casing.

3. An electric switch having a relatively movable casing and cover, said casing adapted to form one of the poles of the switch, means yieldingly connecting them, and a flexible electric conductor secured in positive electrical connection with said casing and cover.

4. An electric switch having the combination of a casing, a contact member contained therein, a cover for the casing comprising a contact-member, movable switch mechanism including a switch rod arranged to engage the contact member within the casing, and a brush member arranged to engage the cover, said casing and cover arranged for relative movement therebetween upon a circuit interruption, and a flexible electric connector secured in positive electrical connection with said cover and casing.

5. An electric switch having the combination of a fixed cover arranged to form a contact member of the switch, a relatively movable casing disposed beneath said cover, means yieldingly to support said casing in position beneath said cover, a contact-member mounted in and electrically connected with said casing and a movable switch-member including an independently-supported switch rod arranged to engage the

contact member in the casing and a brush member arranged to engage the cover of the casing.

6. An electric switch having the combination of a cylindrical casing, a cover for the casing, an insulating bushing having an aperture therein carried by said cover, a contact member contained within and electrically connected with said casing, a movable switch member including an independently-supported switch rod movable within said bushing to engage said contact member and a brush member arranged to engage the cover, supporting means for said casing and cover arranged removably to support the cover and support the casing yieldingly beneath the cover.

7. An electric switch having the combination of a cylindrical casing, a cover for the casing, an insulating bushing having an aperture therein carried by said cover, a contact member contained within and electrically connected with said casing, a movable switch member including a switch rod movable within said bushing to engage said contact member and a brush member arranged to engage the cover, supporting means for said casing and cover arranged removably to support the cover and support the casing yieldingly beneath the cover, said supporting means including a base, rods secured to said base extended upwardly along the casing and fixed to said cover, and a spring carried by said base engaging the lower portion of said casing.

8. An electric switch having the combination of a cylindrical casing, a cover for the casing, an insulating bushing having an aperture therein carried by said cover, a contact member contained within and electrically connected with said casing, a movable switch member including a switch rod movable with said bushing to engage said contact member and a brush member arranged to engage the cover, supporting means for said casing and cover arranged removably to support the cover and support the casing yieldingly beneath the cover, said supporting means including a base, rods secured to said base extended upwardly along the casing and fixed to said cover, and a spring carried by said base engaging the lower portion of said casing, lugs carried by said base arranged to engage the lower portion of said casing and restrain it from lateral movement and said cover having a flange received within the upper portion of said casing and engageable therewith to restrain it from lateral movement.

9. An electric switch having a cylindrical

casing adapted to contain oil, a contact member mounted in the lower portion of said casing beneath the oil therein, a switch rod movable within said casing to engage said contact member, a baffle plate having a vent aperture through it received in said casing under the cover and yielding supporting means for said baffle plate.

10. An electric switch having a cylindrical casing adapted to contain oil, a contact member mounted in the lower portion of said casing beneath the oil therein, a cover for the casing, a switch rod movable within said casing to engage said contact member, a baffle plate having a vent passage through it received in said casing under the cover, and means yieldingly to support said baffle plate in position.

11. An electric switch having a cylindrical casing adapted to contain oil, a contact member mounted in the lower portion of said casing beneath the oil therein, a cover for the casing, a switch rod movable within said casing to engage said contact member, a baffle plate received in said casing under the cover, and means yieldingly to support it in position including rods on which said plate is slidably received, and springs arranged on said rods to support said plate yieldingly in position.

12. An electric switch including a cylindrical oil receptacle, flexible means to support said receptacle yieldingly including a support disposed beneath said receptacle, a spring carried by said support and disposed in engagement with the bottom of said oil receptacle in the middle of said bottom, and inflexible means to support said receptacle movably in vertical position on said spring.

13. An electric switch including a support, a helical compression spring carried by said support, and a cylindrical oil receptacle having its bottom resting on said spring with the axis of said receptacle approximately co-incident with the axis of said spring.

14. An electric switch including an oil receptacle having a reduced neck at the bottom thereof, and yielding supporting means in engagement with said neck.

15. An electric switch having a relatively movable casing and cover, said casing adapted to form one of the poles of the switch and means yieldingly connecting said casing and cover including a yielding electric conductor electrically connected with said casing and cover.

In testimony whereof, I have signed my name to this specification.

GEORGE A. BURNHAM.
